UNITED STATES PATENT OFFICE.

ROBERT PAULING AND JOSEPH SUTTER, OF LEWISTOWN, MONTANA.

DESIGN FOR A GEARING-FRAME FOR CHURNS.

SPECIFICATION forming part of Design No. 33,479, dated October 30, 1900.

Application filed October 4, 1900. Serial No. 32,056. Term of patent 14 years.

To all whom it may concern:

Be it known that we, ROBERT PAULING, a citizen of Great Britain, and JOSEPH SUTTER, a citizen of the United States, both residing at Lewistown, in the county of Fergus and State of Montana, have invented and produced a new and original Design for a Gearing-Frame for Churns; and we do hereby declare the following to be a full, clear, and exact description of the invention, such as will enable others skilled in the art to which it appertains to make and use the same.

Our invention relates to a new and original design for a gearing-frame for churns; and the design consists of the essential characteristics, substantially as shown in the accompanying drawings and hereinafter more specifically described.

Figure 1 represents a perspective view of the gearing-frame, and Fig. 2 is a vertical sectional view of the same.

1 designates a curved approximately semi-circular flat base.

2 2 designate a pair of oppositely-situated legs, which are connected with the base-plate 1 near its ends and which legs are also connected with a hollow substantially rectangular frame 3, set in an upright position upon the said legs.

3 4 designates a loop or ring of a somewhat flattened form, mounted upon the upper end of the frame 3.

5 designates a leg mounted upon the plate

1 in the region of its central portion and extending in a curve toward the frame 3. This 35 leg 5 connects with an upright 6, spaced from the frame 3 and in a line approximately parallel therewith, the said upright having its upper end extending at right angles toward the frame 3 and connected therewith. 40

Upon the rear side of the upright 6 is a cylindrical boss 7, and at the rear side of the frame 3 is a flat plate or partition 8, provided with an opening, the center of which is in an axial line with the center of the cylindrical 45 boss 7 referred to.

In the upper portion of the frame 3 is an opening 9, and in the lower portion is an opening 10, which passes entirely through the bottom end of the frame. 50

More particularly stated, the essential features are the curved base-plate 1, the upright frame 3, the legs 2 2 and 5, connecting said frame with the base-plate, the upright 6, and the looped member 4. 55

What we claim is—

The design for a gearing-easing for churns and like machines, substantially as herein shown and described.

In testimony whereof we affix our signatures in presence of two witnesses. 60

ROBERT PAULING.
JOSEPH SUTTER.
